UNITED STATES PATENT OFFICE.

ALPHONSO S. KEATING, OF CORRY, PENNSYLVANIA.

COMBINED SIGNALING AND ALARM SYSTEM.

Application filed December 19, 1919. Serial No. 346,038.

To all whom it may concern:

Be it known that I, ALPHONSO S. KEATING, a citizen of the United States, residing at Corry, in the county of Erie and State of Pennsylvania, have invented certain new and useful Improvements in a Combined Signaling and Alarm System, of which the following is a specification.

This invention has relation to telegraphic and telephonic dispatching systems and apparatus, as well as signaling and electric alarm systems, and has for an object to provide a system including apparatus and wiring connection therefor designed for military use.

Another object of the invention is to provide a system and apparatus of the character above set forth embodying means for silently transmitting and receiving a message in the Morse or other code.

Another object of the invention is to provide a combined apparatus for the silent transmission and reception of messages in telegraphic code, and for the transmission and reception of oral messages by means of the same apparatus.

Another object of the invention is to provide a system of the character above set forth embodying a combination of said devices whereby messages may be transmitted and received in telegraphic code, either audibly or silently, and where messages may be transmitted and received audibly through the medium of telephonic apparatus.

A still further object of the invention is to provide improved transmitting and receiving devices designed particularly for use in connection with other apparatus of my system and designed particularly to meet the conditions to be imposed thereupon in practice.

A still further object of the invention is to provide in a dispatching and alarm system, devices to be located at each end of the line whereby to actuate a signal when the lines are tampered with or severed.

A still further object of the invention is to provide a time controlled mechanism in a combined dispatching and alarm system whereby the operation of the alarm mechanism mentioned above is placed in circuit during certain periods of the day, and the apparatus thrown out of circuit during the remainder of the period.

A still further object of the invention is

to provide an audible signal and local circuit therefor, in a combined dispatching and alarm system having the characteristics above set forth, for insuring the constant operation of the signal when actuation thereof is initiated.

A still further object of the invention is to provide means in a combined dispatching and alarm system whereby the use of either closed-circuit battery, such as a gravity cell, a storage battery, or a dynamo source of energy, may be employed, or in place thereof, an open-circuit element such as a dry cell may be employed without detriment to the dry cell from polarization in the use thereof.

A still further object of the invention is to provide a by-pass circuit in a combined dispatching and alarm system, whereby should the main lines become crossed accidentally, or otherwise crossed, the by-pass circuit would serve to complete a main line circuit, in which case, both the main lines, though crossed would form but one side of the main line circuit, the earth, in combination with the station wiring of the invention, the other side of the circuit.

In addition to the foregoing my invention comprehends improvements in the details of construction and arrangement of the parts to be hereinafter more fully described and particularly set forth in the appended claims.

The drawings illustrate a preferred embodiment of the invention. However, it is to be understood that in adapting the same to meet different conditions, various changes in the form, proportion, and minor details of construction may be resorted to without departing from the nature of the invention as claimed hereinafter.

In the accompanying drawings in which similar and corresponding parts are designated by the same characters of reference throughout the several views in which they appear:—

Figure 1 is a diagrammatic view illustrating the wiring connection between the various elements of my apparatus and setting forth the relation between two stations.

Figure 2 is a detail view in side elevation illustrating the telegraphic receiving apparatus closely associated with the switch mechanism for controlling the operation thereof.

Figure 3 is a view in front elevation of the apparatus shown in the immediately preceding figure.

Figure 4 is a view in plan of my improved 5 telegraph key for use in connection with my apparatus.

Figure 5 is a side view of the telegraph key bar with contact points and adjustment screws.

10 Figure 6 is a view in side elevation on an enlarged scale of the circuit closing apparatus designed to be actuated when the lines are tampered with or severed, and

15 Figure 7 is a view in front elevation of the time controlled circuit closing mechanism.

With reference to Fig. 1 of the drawings, A and B indicate connected stations. The parts of each are duplicated, hence like 20 numerals are used to designate corresponding parts of both stations. However, the numerals of station B are primed to prevent confusion.

Referring to Figs. 2 and 3 of the drawings 25 which illustrate in detail the apparatus including the telegraphic receiving mechanism and the telephonic transmitting and receiving apparatus, with a switch hook for supporting the telephonic receiver, 10 indicates a base board supported by an arm 11 pivoted at 12 to a standard 13 of a desk set. Mounted upon the outer face of the base board 10 is a base plate 14 designed to carry the apparatus. At the upper end of the 30 base plate is an anvil bracket 15 of the type usually provided in connection with telegraphic receiving apparatus. A second bracket 16 is located a distance below the anvil bracket 15 and is provided with oppositely disposed adjustment screws 17 for pivotally supporting a vibrating bar 18 which has one end mounted between said screws 17 and the opposite end extended toward the anvil bracket 15 and provided with an adjustment screw *a* designed to coact with an adjustment screw *b* of the anvil bracket 15 to limit movement of said vibrating bar 18 in the usual manner. Mounted upon the base plate 14 between the brackets 35 15 and 16 is a pair of electro-magnets 19. An armature 20 carried by the bar 18 is adapted to be attracted by the electro-magnets 19. The armature 20 is preferably in the form of a flat ring of a sufficient diameter to be brought into proximity to the poles of both magnets 19 simultaneously. To the end of the vibrating bar 18, adjacent its point of pivotal mounting, is connected an extending hook 21 to the end of which 40 is connected one end of a coil spring 22, the opposite end of said coil spring 22 extending toward the anvil bracket 15 and being connected to a threaded rod 23 which is loosely mounted in said bracket and which has an adjustment nut at each end to en-

gage the bracket, whereby the tension of the spring 22 may be varied.

Connected to the lower bracket 16 is a strip of metal which has its lower end bent towards the base to form an arm 24 and its upper end bent outward to form an arm 25. The intermediate portion of said strip attached to the bracket 16 is electrically insulated therefrom. A casing 26 is carried by the arm 25 and preferably forms a part thereof. The casing 26 is a part of the telephonic transmitter and is preferably of metal, being threaded externally to receive a cap 27. Located within the casing 26 is a second circular casing, or cup 28, formed of material of said casing 26 and of which casing the cup forms a part, in the bottom of which is placed a carbon block 29 secured thereto by means of a screw 30 which penetrates the block 29 and the casing 26. The block 29 is insulated from the casing 28. A ring 31 of insulating material is closely engaged with the inner wall of the casing 28, and a number of spheres 32 of carbon are placed in the casing 28 in contact with the block 29, the casing 28 being subsequently closed by a diaphragm 33 which is retained in place by means of the cap 27. It will be noted that the ring 31 serves to prevent contact of the diaphragm 33 and carbon spheres 32 with the casing 28. To the rear end of the screw 30 there is secured a conducting strip 34. The lower end of the strip 34 is secured between the bracket 16 and the strip attached thereto forming the arms 24 and 25 and is insulated therefrom. The strip 34 connects electrically with the outer end of a flat spring contact finger 35 which likewise is held or clamped between said bracket 16 and part 24-25, contact finger 35 being insulated from bracket 16. The contact finger 35 extends towards the base 10, its rear end tending to spring downward. Pivotally mounted upon the lower end of the arm 24 is a telephone receiver hook 36, which is formed with an upper projection 37 and a downward projection 38. These projections 37 and 38 are disposed above and below the pivot support of the receiver hook. A projection 39 extends forwardly from the pivot end of the receiver hook and is normally engaged by a spring finger 40 rigidly secured to the intermediate portion of the strip forming the arms 24 and 25. The spring 40 acts to normally urge the outer end of the receiver hook in an upward direction. The outer end of the receiver hook is depressed against the tension of the spring 40 by the weight of the receiver 41 suspended therefrom. The projection 37 of the receiver hook bears against the under side of the flat spring finger 35 to normally retain the same in engagement with contact member 42 mounted upon the plate 14 but electrically insulated 70 75 80 85 90 95 100 105 110 115 120 125 130

vector or vectorially in the manner above stated and proceed to contact switch 32 being bypassed, contact point 423. The tap selector receiver indicated at Fig. 29 comprises a housing 126 and cap 128. A diaphragm 147 is interposed between the housing and cap, and it is held in place when the cap is engaged with the housing. Within the housing 126 is a core 125 which is surrounded by a coil of wires 98, having its terminals extended through the housing absolutely insulated from the main trunk or coil of turns as compared to the number of turns in the coil 149. The terminals of the coil 126 are twisted together to form a local inductive closed circuit to the greatest extent 428, said inductive circuit having inductiveness in common with the core 125 and the diaphragm 123 when said circuits are energized.

The telegraphic key illustrated in the portion 100 of Figs. 4 and 5 comprise the conventional elliptized base plate 55, having 2 supports 52 to support the key 53 in which the intermediate position of the key 53 is shielded from vertical oscillation. At one end of the plate 55 there is located a contact point 56 insulated from the base plate 55 and which is in direct electrical connection with a contact clip 57. At the opposite end of the base plate 55 there is located a binding post 58 in electrical communication therewith. Binding posts 57 and 58 are mounted upon the base plate 55 in insulated relation therefrom. The post 57 is in electrical communication with the contact clip 56 by means of a conductor 59.

extending inwardly adjacent to the binding post 63 is an lug 59 from which is integrally within the base plate 31 and adapted to receive a pin 60 from the seton from the switch lever 62 supported on the lug 59 and having a thumb piece or handle 63. The inner end of the switch arm 61 is curved, as at 64, to provide a shaped portion to engage around the pin 60 and be movable in contact with an conduct clip, —^{an}— in electrical communication with the post 55, but not to extend beyond a slot allowing the opposite end of said switch 62 to engage in the contact clip portion of the lug 55.

transmitter in station B, through rod 87', contact 89' and wire 65'. The said main line 66 may be considered as extending from its contact with the transmitter casing 26 through the same, the diaphragm 33, carbon spheres 32, carbon block 29, contact strip 34, flat spring contact finger 35, terminating in the free end of said contact finger. It may also be considered as extending from its contact with said casing 26 through the said casing, the arms 25 and 24 and the receiver hook 36 in which it terminates. The main line 66, thus diverges into two branches, alike in both the stations A and B. When the metal branch path, including the transmitter casing 26, the arms 25 and 24 and the receiver hook 36, is brought with its terminal 37 in contact with the free end of the contact finger 35 by means of suspending the telephone receiver 41 on the receiver hook 36 or by means of the contact finger 35 in its downward tendency, mentioned above, making contact with its free end with said contact point 37 of hook, the two branches are united and form dual paths of the main line circuit, one of which forms the telephone transmitter carbon element path. The other forms the metallic shunt path to said carbon element path. The circuit thus ends in corresponding points at both stations A and B. Such points may be considered as the equivalent of movable switch arms to direct the main line circuit through the telegraphic part of the circuit, or through a telephone receiver circuit. These circuits will be described in detail hereinafter after the parts with which they associate have been described.

The lower contact member 43 is connected by means of a conductor 67 to one terminal of the coil 49 of the telephone receiver. The other terminal of the coil 49 is connected by means of a conductor 81 to a two-way switch 73. The contact points 71 and 72 are provided to co-operate with switch 73, to either of which said switch may be brought into engagement. The contact points 71 and 72 are connected by means of a conductor 74, having a battery 75 interposed therein. The contact finger 44 is connected by means of a conductor 68 to the conductor 81. The contact member 42, designed to be normally engaged by contact finger 35 and contact point 37 of the receiver hook 36, is connected by means of a conductor 70 to one terminal of the electro-magnet 19 of the telegraphic receiver. The binding post 56 is connected by means of a conductor 76 through a switch 101 and contact point 102 to the main line 77. The binding post 57, of the key is connected by means of conductor 78 to the conductor 74, adjacent the contact 72, and to the contact clip *c* through the conductor 45'. The electro-magnet 19, of the telegraphic receiving apparatus, has a terminal of its

helix or winding connected by means of a conductor 79 to the conductor 74. The post 58 of the key is connected by means of a conductor 80 to the conductor 79. It will be noted that the main leads 66 and 77 connect at each end with the elements described above through the medium of circuit closers, the detail construction of which will be described later. These connections completely associate the parts of each station for operation in a manner which will now be described.

To transmit a message telegraphically through the medium of the conventional telegraph key and receiving apparatus from station A to station B with the main line circuit arranged for closed-circuit battery use, that is, with the stop pin 60 removed, the switch 62 is closed on the contact clip *c*, the conductor 80 opened, and the switch 73 is placed on contact point 71. The circuit thus formed is alike in both stations A and B. The switch 62 in the sending station A is now opened, and operation of the key bar 54 to send a message results in the formation of a circuit which may be traced as follows: from the (now closed circuit) battery 75 through conductor 78, post 57, wire 45'; contact 55, key 54, key frame 51, conductor 76, switch 101, contact point 102, rod 86, main lead 77, through said conductor 77 to station B, entering station B through rod 86' to contact 102' from which point the circuit takes its course through switch 101', conductor 76', the post 56' on the telegraph key in station B, base 51', switch 62', clip *c*', conductor 45', post 57', conductor 78', closed circuit battery 75', conductors 74' and 79', electro-magnet 19', conductor 70', point 42', dual paths mentioned above, to conductor 65', through rod 87', returning through the main line 66 to station A; entering the station A through rod 87 to the conductor 65 thereof, thence through dual paths, contact point 42, conductor 70 to the electro-magnets 19, thence through the conductors 79 and 74, through battery 75 to conductor 78, the point from which the circuit started. The electro-magnets 19 and 19' of both stations A and B will thus be energized to render audible the telegraph signal formed by the telegraph key of station A.

To transmit a message telegraphically through the medium of conventional telegraph key and receiving apparatus from station A to station B, with the main line arranged for use of open-circuit battery, with the stop pin 60 in place on the key, the switch 62 closed on the contact clip —*a*— on post 58, the conductor 80 connecting the post 58 with the conductor 79, the switch 73 on contact point 72, an open-circuit dry cell 75 being substituted for the closed-circuit gravity cell and dead-ending at both clip *c* and contact point 55, and through switch 73

and points 43 and 44 normally alike in both stations A and B, the switch 62 in the sending station A being open, operation of the key bar 54 to transmit the message, the circuit may be traced as follows:—

From the dry cell, 75, through conductor 78, post 57, conductor 45, contact point 55, key bar 54, key base 51, post 56, conductor 76, switch 101, contact point 102, rod 86, main lead 77 to station B, entering station B through rod 86' to contact 102', switch 101', conductor 76', post 56', key base 51', switch 62', clip —a²—, on post 58', conductors 80' and 79', electro-magnet 19', conductor 70', contact point 42' dual paths, conductor 65', rod 87', returning through the main line 66 to station A entering station A through rod 87 to conductor 65, thence through the dual paths, contact point 42, conductor 70, electro-magnets 19 and conductor 79. As the path through the conductor 80 is now open owing to the switch 62 being open in the sending station A, the circuit flows through conductor 74, dry battery 75 to conductor 78, the point from which the circuit started. The electro-magnets 19 and 19' of both stations A and B will thus be energized to render audible the telegraph signal formed by the telegraph key in station A. When using an open-circuit dry cell, the circuit formed to transmit the message telegraphically, differs from that of the closed-circuit cell, in that the circuit does not pass through the open circuit dry battery 75' in station B, but through the conductor 80' the dry battery of the sending station A operating the main line circuit and the instruments therein. However, should the operator at the receiving station B open his switch 62 and hold key lever 54 depressed on contact point 55 the battery of said station B will be introduced into the circuit with its accompanying benefit. It is optional with the operator of the receiving station to do so or not. The keys 62 are closed normally and the main line circuit is metallic including no battery, the dry cells, in both stations, standing open at their respective contact points.

To send call by means of the receiver hook 36, it does not matter whether the main line circuit is arranged for use of closed-circuit battery, or for the use of the open circuit dry cell, the manner is, simply, to remove the telephone receiver from the receiver hook 36. In the upward movement of the receiver hook the contact point 38 of said hook is caused to wipe over the contact finger 44 establishing the main line circuit through the battery 75. The momentary contact of point 38 with the point 44 of the contact finger causes an electrical impulse to be sent over the main line through the apparatus in the distant station B, causing the said instrument to re-

spond audibly to such impulse. In the removal of the receiver from the receiver hook, the contact point 37 of said hook, in conjunction with the contact finger 35, opens the main line circuit, and the path 70 through the electro-magnets 19, at point 42, in its upward movement. It, however, reestablishes the main circuit during the wiping process of the point 38 over the part 44, as above described. In the opening of the main line circuit, at point 42, by removing the receiver from the hook 36, free end of contact finger 35 retains contact with point 37 of the receiver hook, in its passage over and during the wiping contact of point 38 with point 44, due to the downward spring tendency of flat spring contact finger 35. Thus the metallic path and shunt is preserved across the carbon element, contact finger path, not only during the wiping process but during the normal contact of hook and contact finger at point 42. Owing to this feature, the dual paths of the main line circuit may be considered as non-resistant to the passage of the current in the main line circuit.

In sending the call by means of the receiver hook, the main line circuit being arranged for the use of closed-circuit battery, that is, with the conductor 80 open at post 58, or said conductor removed entirely, the stop pin 60 is removed to allow the switch arm 62 to make contact with the contact clip c. Though the hook-formation part 64 of said switch 62 makes contact with clip —a²— it is not in effect, as the path is opened by the removal of the conductor 80. With the switch 73 on contact point 71, the path of the circuit may be traced as follows:

From the point of wiping contact 44, through conductor 68, conductor 81, switch 73 on contact point 71, conductor 74, the route through the magnet 19 being open at contact member 42, the circuit takes its course through the battery 75, conductor 78, post 57, conductor 45, clip c, switch arm 62, key base 51, post 56, conductor 76, switch 101 to contact point 102. From point 102 of station A, the circuit flows through the rod 86, main line 77 to station B, entering station B, through rod 86' to contact point 102' from which point the circuit takes its way through switch 101', conductor 76' to post 56', on telegraph key, thence through the key base 51', switch arm 62', clip c', conductor 45', post 57', conductor 78', battery 75', (as the route through switch 72', on point 71', is open at the contact points 43' and 44', and, as the telephone receiver is on the receiver hook, in this station and the main line, thereby closed at point 42'), the circuit takes its course through the conductor 74', conductor 79' electro-magnets 19', conductor 70', 130

contact member 42' dual paths to conductor 65', through rod 87' to main line 66 returning through the main line conductor 66 to station A, entering station A through the rod 87 to the conductor 65 thence through the dual paths contact point 38 of hook in wiping contact with contact finger 44 the point from which the circuit started. The electromagnet 19' of station B will thus be energized to render audible the call signal formed by the receiver hook in station A. While the calling signal is automatically sent in removing the receiver from the hook, it may be repeated manually in the passing and re-passing of the contact point 38 of receiver-hook over contact member 44. It is to be noted, that in the calling circuit both the closed-circuit battery of station A and the station B are included in the main line circuit; also, that the magnets 19' only, of station B are included in the said circuit, the terminal of the magnets 19 of station A being dead-ended in contact member 42.

In sending the call by means of the receiver hook, the main line circuit being arranged for the use of open circuit battery, that is, with the conductor 80 connecting post 58 with conductor 79, the stop pin 69 in place allowing the hooked end 74 of switch 62 to make contact with contact clip —a²— but preventing contact of the arm of said switch 62 with the contact clip c and thereby dead-ending the open-circuit battery 75 at said clip c, and the contact point 55 being in contact with said clip and with the switch 73 now on contact point 72, the circuit may be traced as follows:

From the point of wiping contact 44, through conductor 68, conductor 81, switch 73, contact point 72, conductor 74, to battery 75, (as conductor 78 tapping the conductor 74 adjacent the contact point 72, is dead-ended at its other end in contact clip c and contact point 55,) the circuit takes its course through battery 75, conductor 74, to the intersection of conductor 74 with the conductors 80 and 79. (As the path through the conductor 79, electromagnet 19 and conductor 70 is open in the contact member 42), the circuit takes its course through the conductor 80, post 58, clip —a²—, the hook portion 64 of switch 62, the base 51 of the telegraph key, post 56, conductor 76, switch 101, contact point 102, thence through the rod 86, main line conductor 77, from station A to the station B, entering the station B through rod 86' to contact point 102' from which point the circuit takes its course through switch 101', conductor 76', post 56', key base 51', switch 62', and hooked portion 64' thereof, through the clip —a²'— conductor 80', (as conductor 74' through battery 75' is open at point c' and 55'), the circuit takes its course through the conductor

79', electromagnets 19', conductor 70', contact member 42', dual paths to conductor 65', returning through main line, conductor 66 to station A, entering station A through rod 87, the conductor 65 from whence the 70 circuit takes its course through said conductor 65 and the dual paths to their common junction at point 38 in wiping contact with the contact finger 44, the point from which the circuit started. The electro-magnet 19' in the receiving station B will thus be energized to render audible the call signal formed by the receiver hook in the station A. It is to be noted, in this case, in the use of the open-circuit battery, that the 80 battery of the calling station A, only operates the main line circuit and the magnets 19' therein of station B, that the electromagnet 19 of the station A stands with its end open in the contact member 42, as in 85 the case of use with the closed circuit cell.

In sending the call by means of the receiver hook 36, as the contact point 38 of said hook leaves its wiping contact, the contact finger 44, the contact point 43 engages 90 the point of contact finger 35 preventing its further advancement downward, the contact point 38, however, continues onward to the extent of the upward movement of the receiver hook, thereby the main line circuit is formed through the carbon element contact finger path, the contact member 43, conductor 67, the magnet coil 49 of the telephone receiver, conductor 81 to the switch 73. The shunt formed across the carbon element contact finger path is automatically opened, when the contact point 37 of the receiver hook, (the terminal of the shunt path), severs contact with the contact finger in the further advancement upward of receiver hook, the shunt path standing dead-ended in the contact point 37 of the receiver hook. This circuit, with the main line circuit arranged for use of closed-circuit battery, and which circuit designates the telephone circuit, may be considered as well, the telegraphic silent call and message circuit. It may be traced as follows: Starting from point of contact of contact finger 35 with contact member 43, the circuit takes its course through the conductor 67, magnet coil 49, of receiver, conductor 81, switch 73, contact point 71, conductor 74, through closed-circuit battery 75, conductor 78, post 57, conductor 45, clip c, switch arm 62, in contact with said clip, key base 51, the post 56, conductor 76, switch 101, contact point 102, rod 86, main line 77 from station A to station B, entering station B through rod 86' to contact point 102' from which point the circuit takes the course through conductor 76' to key post 56', through key base 51', switch 62', contact clip c, conductor 45', post 57', conductor 78' and battery 75'. As the operator in station B receiving the call 100

130

ing the station $\frac{1}{2}$ through coil 87 to the condenser 88, thence through the carbonaceous contact conduct of bigger plate to the contact conduct 453, the point from which the circuit is started. This circuit, with the main line arrangement for the use of the specimen circuit, may be traced as follows: From point of contact stage 83, with contact number 451, the circuit takes its course through the condenser 87, magnet coil 491, the telephone receiver, condenser 831, switch 832, and contact point 25, through the normal open contact of the open-circuit dry cell, condenser 744, to point of contact of condenser 830; thence with (as the path through the condenser 744) (as the path in contact number 452,) the circuit takes the course through the condenser 830, point 153, contact dipper— $\frac{1}{2}$ —, and curved end 36, to switch 62. (It will be noticed that the switch arm of switch 62 does not make contact with the contact dipper, and that both the dipper and contact points 36 stand open, and therefore closed.) Therefore, the circuit takes the course through the said switch, dry stage 515, point 516, condenser 746, switch 101, contact point 102, rock 86 through main line condenser 771 from station A to station B, continuing section B through rock 866 to contact point 102, to switch 101, from which point the circuit takes its way through condenser 746, point 516, dry stage 511, switch 621, and curved end 36; thence, dipper— $\frac{1}{2}$ —, point 513 condenser 830 to its contact with condenser 742. (At the operation in station B this receiver has received from coil 87 the received load in answer to the call, the path through the condenser 742, detector projects 191, condenser 742 is open, and (as indicated in the contact number 452) the circuit, the circuit takes its course through contact point 742, switch 73, through condenser 811 (as condenser 831 having condenser 811 as open, and therefore indicated in contact point 454, the receiver has

This sending of the call, may be effected either by the telegraph key, or by means of the receiver. In the ordinary case the call will be fully intelligible. Should the call prove elusive, circuit telegraphically and in manner as before, it will be necessary that specified blocks be sent apart from this transmission, and when circuit number is signalled by respective operators. At such time the operator in station A, in giving the call, will first open his key, then encode this message from the receiver block. The object in first opening the telegraph key is to open the main line so that each of the contacts point 88 off the receiver block may be over the contact. If a call is made the signal will be sent over the line because a fully reliable alarm, in which case, the call is signalled will be transmitted by means of the key. With this circuit arranged for use of the direct-current battery, the circuit may be traced as follows:—from the point 15 off the telegraph key, through the key block 34, key base 33, post 34, combination 36, switch 1011, contact point 102, coil 183 through main line conductor 777, from station A to station B, entering block station B, and 186 to contact point 102, to switch 011, conductor 776, post 186, key base 31, switch 022, clip 2, combination 35, post 34, combination 768 to central circuit battery 725. If the operator at station B is not at his post, he will not leave unopened his telephone receiver, from off the receiver block, the core of the circuit will make the required through block conductor 764, conductor 761, magnet coils 182, combination 770, contact number 42, closed path to conductor 363 through the same coil 187 returning to station A through conductor 777, 183, entering station A, through the coil 377, conductor 186, conductor between contact 188, 189, combination 186, conductor 771, 187, conductor 78, post 37, conductor 446, to contact point 187, the point from which the circuit is started.

As the transmitter consists of structures and

the winding of the magnet coil 49 of the telephone receiver is included in the circuit just described, the resistance thereof in the circuit would so reduce the strength of the current flowing in said circuit that it would not be strong sufficiently to magnetize the magnets 19', in station B so as they would attract the armature 20 as to cause it to give forth an audible signal.

10 However, should the operator be at the station B, expecting to receive a call, he would have removed his receiver from the receiver hook and placed it in position with its receiving end exposed to emit the signal, which in this case, would be given by the diaphragm 33', of the telephone receiver. Therefore, the path of the circuit from the battery 75' in station B would not be through the conductor 74', and magnets 19' 15 to conductor 65', but through the switch 73' on contact point 71', conductor 81', magnet coil 49' of the receiver, conductor 67', contact point 43', contact finger-carbon element path of the transmitter to the conductor 65'. 20 25 The circuit being thus established, the diaphragm 33 of the telephone receiver in the station B, likewise the diaphragm of the receiver in station A, will cause to be set up a low toned signal in answer to the signal formed by the telegraph key in the station A. Such low tones of the call signal being heard by the operator at his station. And, with the receivers to their ears, the operators will receive the message only transmitted by 30 35 the key of station A.

With the circuit arranged for the use of the open circuit dry battery, in sending the call or message by use of the telegraph key, telegraphically and in a manner silently, the telegraph key is first opened and the receiver then removed from the receiver hook for reason explained above in relation to the use of closed-circuit.

40 When the telegraph key in station A is used, the path of the circuit may be traced as follows: from the contact point 55 of the telegraph key, through the key bar 54, key base 51, post 56, conductor 76, switch 101, contact point 102, rod 86 to main line conductor 77 to station B, the circuit entering station B through rod 86' to contact point 102' to switch 101' through conductor 76', post 56', key base 51', the curved end 64', of switch 62', (the arm of switch 62' being out 45 of contact at clip c') the circuit takes the course through contact clip —a²—, post 58', conductor 80' to junction with conductor 74'-79'. Should the operator in station B be not at his station, (as the path through conductor 74' and battery 75' will be open 50 at contact points clip c' and contact 55' of the key, also through switch 73' on contact point 72', at points 43' and 44'), the circuit takes its course through conductor 79' magnet coil 19', conductor 70', contact member

42', dual paths to conductor 65', returning through conductor 66 to station A, entering station A through rod 87, conductor 65, casing 26, member 35, contact member 43, through conductor 67, receiver coil 49' (as the conductor 68 is open in the contact point 44) the circuit takes its way through conductor 81, switch 73 on contact point 72 (as the circuit through the battery 75, conductor 74, through conductor 79, magnets 19, conductor 70 to contact point 42, or through conductor 80 to contact clip a²), switch 62 being open, the paths dead end in their respective contact point 42 and a², the circuit takes its course through conductor 78, post 57, conductor 45 to contact point 55 the point from which the circuit started.

Should the operator in station B be expecting a call and be at his instrument, he would have first opened his key then removed his telephone receiver from the receiver hook, as in the use of the closed-battery use as set forth above, in which case, the circuit in station B would be traced from the junction of conductors 74' and 79'. (As the path through the conductor 79' and magnets 19' would be opened in the contact member 42' in the removal of the receiver), the circuit would take its course from the point of junction of conductor 80', through conductor 74', battery 75' (as the path through conductor 78'-45' is open and dead-ended at clip c' and contact point 55', the operator in station B having closed his switch 62' on clip —a²—,) the circuit continues through switch 73', contact point 72', conductor 81'. As the conductor 68' tapping conductor 81' is open and dead-ended in contact finger 44', the circuit takes the course through the magnet coil 49', the telephone receiver, conductor 67', contact finger-carbon element path through transmitter casing 26' to conductor 65'. The main line circuit thus, being established through this part of the circuit, the diaphragm 46' of the telephone receiver in the station A, will be caused to set up a low-toned signal in answer to the signal formed by the telegraph key in the station A, such low signals given by the diaphragm being heard, only by the operator in the stations when near their respective instrument. With the telephone receiver to the ear, the operator only will receive the telegraphic message transmitted by the key in station A. To receive 110 the silent message with the use of the open circuit battery, it becomes obligatory on the part of the operator at the receiving station that he close his switch 62'. To depress his key while the operator at the sending station is oscillating his key lever 54, would be, to be depriving the line circuit of battery current to operate line circuit. The receiving station supplies the current for the line when its switch 62' is closed.

Obviously, these messages can be transmitted by means of a telegraph key from the station B to station A and received at the station A by means of the telephone receiver 5 by a repetition of the circuits traced above.

For ordinary telephone communications, where the messages are transmitted orally, the call to attract attention of the operator at the distant station may be transmitted by 10 simply removing the telephone receiver from the receiver hook. Both the calling circuit and the talking circuit is formed automatically in the upper movement of the receiver hook as described above. No further change is made, as in the opening, or in 15 the closing of switches whatever in the form of the circuit used.

The coil 50 on the same bar 48 with the coil 49, the terminals of the coil 50 being 20 simply twisted together is used as an auxiliary to the transmission telephonically. I have described above the formation of an inductive circuit in relation to this coil 50.

Attention is next directed to a protective 25 circuit which applies directly to the circuit formed for the transmission of either telegraphic or telephonic transmission. A two-way switch 101, the free end of which rests on a contact point 102 is provided. Attention to such switch and point in the conductor 76 has been called thereto in descriptions given in the circuits hereinbefore 30 described and in which the conductor 76 and switch 101 formed a part. Adjacent the contact point 102 is a second contact point 103. To the contact point 103 is connected one end of a conductor 129, the other terminal of said conductor connecting with a contact point on which rests the free end of 35 a common switch 130, the pivoted end of the switch connecting with the earth through a conductor at point e.

Thus it will be seen that the elements of 40 the system are so associated electrically, one with the other, as to permit messages to be transmitted telegraphically in the ordinary way, that is with the use of a loud receiver, or silently by use of the telephone receiver, the audible signals of which are not sufficiently loud to be heard by anyone except 45 the operator, and by the use of the telephonic transmitter and receiver for transmitting voice currents in the usual way.

Attention is next directed to the circuit 50 closers operable to initiate actuation of alarm mechanism when the line wires 66 and 77 are tampered with or severed. It will be noted with reference to Fig. 1, that a circuit closing apparatus is interposed between 55 the terminals of the line wires and the apparatus just described. Since the circuit closer at each end of the line is a duplicate in construction to the other, a description of 60 one will suffice for both. Therefore, with reference to Fig. 1, 85 indicates a base board

upon which are mounted a pair of slidable rods 86 and 87. The upper ends of the rods are provided with eyes for connection to the terminals of the lines 66 and 77. Each rod is guided for movement in upper and 70 lower brackets 88 and 89, respectively. The lower bracket 89 of rod 87, is connected to the conductor 65, while the bracket 89 of the rod 86 is connected to the conductor 76, and said conductors 65 and 76 are thus established in communication with the lines 66 and 75 77 through the medium of the said rods 86 and 87.

Mounted in contiguous relation to each of said rods 86 and 87 is a contact strip 90. 80 The terminals of the strips are bent towards the respective rods, and each rod is provided with a pair of collars 91. Each collar has a projection extending towards the strip and each projection is provided with a contact 85 point, designed for engagement with a contact point on the bent end terminals of the strip 90, but normally held out of engagement when the collars on the rods are in intermediate position. Each main line 66 and 90 77 passes at its terminal over a pulley 92 and each of said line wires is connected at a point beyond the pulley with a flexible brace 93 securely anchored at its ends. A coil spring 94 is connected at one end to each 95 end of the line wires 66 and 77 at the point of their connection to the braces 93 so as to retain said line under strain at all times. Each rod 86 and 87 is furthermore provided with a collar 95 having opposed arms, and 100 a coil spring 96 is connected at one end to each of said arms and its opposite end to a bracket f mounted upon the board 85 whereby to urge the rods 86 and 87 downward and to retain the contact point of collars 91 105 normally out of engagement with the strips 90. A contact strip 97 is mounted in contiguous relation to the rod 87 with the terminals of said strip 97 bent towards the 110 rod and provided with contact points designed for contact with contact points of either one of the collars 91 of the rod 87. In the case of the rod 87 the collars 91 are designed for simultaneous engagement with the adjacent ends of the parts 90 and 97. 115 The strips 97 are in electrical communication with the upper bracket 88 of the rod 86 by means of a conductor 98. The strips 90 are electrically connected by means of the end of a conductor 99 which branches, adjacent these strips for connection to both, one of the branches being designated by the reference figure 98a, the other being continued as the end of conductor 99.

It will be seen that if line conductor 66 is 120 tampered with, the rod 86 will move upward so as to engage the contact point of the upper collar 91 thereof against the terminal contact point of strip 90. On the other hand should the main line 66 be severed, the 125 130

springs 95 will act to move the rod 86 downward so as to engage the contact point of the lower collar 91 thereof against the lower terminal contact point of the strip 90. 5 Or should it be the main line conductor 77 that was tampered with, the rod 87 will move upward so as to engage the contact point of the upper collar 91 thereof against the upper terminal contact points of both strips 90 and 97 simultaneously, the ends of strips 97 being of a spring tendency allows the contact points thereof to conform to contact with that of contact points of strip 90 on collar 91. On the other hand should the main line conductor 77 be severed the spring 96 will act to move the rod 87 downward so as to engage the contact points of the lower collar 91 thereof against the lower terminal contact points of both strips 90 and 97 simultaneously. By providing electrically operable alarm mechanism and associating the same with the contact strip 90 of the respective rods 86 and 87 and the strip 97 and 87, it will be seen that the alarm may 20 be caused to sound, or be actuated when the line wires are either tampered with or totally severed.

I have illustrated in connection with this type of circuit closer a specific arrangement 30 of signaling apparatus shown more in detail in Fig. 7. The alarm and signaling mechanism includes an electric bell, a battery, an annunciator and a time controlled circuit closer. The annunciator may be of the conventional type including an electro-magnet and a drop shutter which are included within the illustration shown in Fig. 1 and indicated at 100. The same elements are located 35 at each end of the main line, that is, they are located in a conductor 105, one end of which taps the main line circuit at the point of junction of main line 66 and 65 with the main line 77-66, the said line 105 having electric relation with what may be considered 40 the ends of these respective main line circuits 66 and 77. The other end of said conductor 105 ends in a contact point 118 adjacent the free end of a two-way switch 131 which rests on an idle contact point in 45 station A, the pivoted end of said switch 131 connecting with the earth through a conductor at point *g*, the switch 131' resting on the contact point 118' in the station B. Thus, it will be understood that the considered 50 ends of the main line conductors 66 and 77 dead-end in the idle contact point in the station A, which station may be considered the one to be protected and said considered ends of main line conductors 66 and 77, in the station B, connect with the earth through the switch 131'. The station B may be considered the station to receive the alarm signal when the conductor 105 is automatically brought in contact with the 55 earth by means exterior to that of the switch

131 in the station A, and which means will be described later. The object of the switch 131 in station A and switch 131' in station A is simply to transpose the relation of stations A and B. While in the present illustration, Fig. 1, the free end of the switch 131 is shown resting on the idle contact point in station A designating it to be the station protected and the free end of the switch 131' resting on contact point 118' 70 of the conductor 105' in station B designating it the alarm receiving station. To transpose the said switches as to their contact points in both the stations would cause the station A to now become the alarm receiving 75 station and the station B the one protected. Such transposition becoming necessary at times when station B, which would be the residence station, would become unoccupied, and the station A, the store station to be 80 protected, would become occupied. It is not to be taken that the station B is not 85 protected from entry, means exterior to the circuit of the main line is provided to protect that station and will also be described 90 later.

It will be noted that when the alarm circuit is formed, the earth forms one side of said circuit and the main line conductors 66 and 77, considered as one conductor, form 95 the other side of the said circuit. It is moreover pointed out that crosses accidentally, or otherwise placed across these exterior conductors 66 and 77 would in no wise effect an alarm signal sent over the 100 alarm circuit. The electric bell 106 includes an armature *h* which connects by means of a conductor 123, with the conductor 105 below the magnet coils of the bell 106. Associated with said armature is 105 a contact point which connects by means of a conductor 124 with said conductor 105 at a point above the magnet coils of bell 106. When a current is caused to flow 110 through the main line alarm circuit through the magnet windings of bell 106, the cores of said magnets become magnetized and attract the armature *h*, which armature, in turn makes contact with the contact point of conductor 124, thereby establishing a 115 shunt circuit across the magnet windings of said bell, through which the current now takes its way to the demagnetization of the said magnet cores. In consequence, the armature returns to first position again opening the shunt and in place to again be attracted. So long as the current of the main line flows through the magnet windings, the armature will vibrate and cause the bell 106 120 to sound. A detent 125 in insulated relation 125 to the armature, but connected thereto engages the free end of a drop arm 126, the pivoted end of said arm connects by means of a conductor 128 with the conductor 105 above the magnet coils of bell 106, a conduc- 130

5 tor 127, provided with a contact point, connects below the battery 116^a with said conductor 105, designated 116. When a current of electricity is caused to flow through the
 10 main line alarm circuit through the magnets of bell 106 causing them to attract the armature *h*, the detent 125 thereof is raised thereby disengaging the free end of arm 126 which falls and engages the contact point of conductor 127, thereby forming a local circuit which includes the bell 106 and the battery 116^a. The local circuit thus established, the bell 106 therein continues to sound, even though the main line alarm circuit through
 15 the magnet coils of said bell is opened and discontinued. To stop the ringing of bell 106 it becomes necessary to restore the drop arm 126 to the upright normal position engaging the detent 125 after the main line
 20 alarm circuit has been discontinued. The restoring is performed manually.

25 A conductor 99, at the upper end of which a branch thereof connects with the strip 90 adjacent the rod 86, and which is tapped by the conductor 98^a, taps with its lower end, the conductor 105, designated 116 at a point below the battery 116^a. The conductor 99, together with that portion of the conductor 105 which includes battery 116^a
 30 and the electric bell 106, and connected thereto, the rod 86 and in association therewith, the rod 87, through means of the contact points 90 and 97, and the conductors 98 and 98^a, forms a local circuit which is adapted to be closed by means of the contact points of collars 91, of rods 86 and 87, when the main line 66 or 77 is tampered with or severed.

35 Having thus described my invention, what I claim as new and desire to secure by Letters Patent is:—

40 1. In a combined telegraphic and telephonic system, the combination with the main line, of a telegraphic receiver, a telegraphic transmitter, a circuit connecting said elements to the main line, and a second circuit including a telephonic transmitter, a telephonic receiver, and a switch for connecting said circuit to the main line, and for connecting the telegraphic transmitter into the telephonic circuit and cutting out the telegraphic receiver.

45 2. In a combined telegraphic and telephonic system, provided with a plurality of stations, each station including a circuit including a telegraphic transmitter and a telegraphic receiver in circuit with the main lines, a second circuit including a telephonic transmitter and a telephonic receiver, a source of current for energizing said circuits, a receiver supporting switch to normally disconnect the telephonic circuit from the main line, said switch when operated connecting said telephonic circuit to the main lines, and a third circuit including a contact under control of the receiver supporting

50 switch adapted to be intermittently energized when the receiver supporting switch is actuated to transmit a current impulse from said source to the main line to actuate the telegraphic receiver of the next station. 70

55 3. In a combined telegraphic and telephonic system, a plurality of stations each including a telegraphic circuit including a telegraphic transmitter and receiver, a telephonic circuit including a telephonic transmitter and receiver, a source of current for energizing said circuits, a pair of spaced contacts, one contact being in the telegraphic circuit and the other in the telephonic circuit, a finger movable therebetween, a telephonic receiver 80 supporting switch arm engaging, when supporting the receiver the finger to retain the same in engagement with the contact of the telegraphic circuit, the receiver hook when raised permitting the finger to engage the other contact to throw the telephonic circuit into communication with the transmitter of the telegraphic circuit, and a third circuit including a contact finger engageable by the receiver hook during upward movement thereof to intermittently energize the transmitter of the telegraphic circuit to actuate the telegraphic receiver at the next station. 85

60 4. In a combined telegraph and telephone instrument, a base plate, electro-magnets mounted thereon, a bracket at one side of said magnet, an anvil bracket on the other side, a vibrating arm pivoted at one end upon the first bracket, and having its other end movable in the anvil bracket, an annular armature carried by said arm attractable by the magnets, spring means for normally retaining the arm away from the magnet, a strip secured at its intermediate portion to the first bracket and having its terminals extended in opposite directions, a telephonic transmitter mounted upon one terminal, a switch lever pivotally mounted on the other terminal, a telephonic receiver, carried by the outer end of said switch lever, projections on said switch arm, a pair of spaced contacts mounted on the base plate, a spring finger mounted in insulated relation upon the first bracket having its terminal movable between the contacts, a projection on the switch arm to engage the finger to normally retain the finger in engagement with one contact, the second contact being intermittently engaged by the remaining projection on the switch lever and electrical connections between the telephonic transmitter and telephonic receiver forming circuits controlled by the movement of the switch arm. 110

65 5. A combined telegraph and telephone instrument including a base plate, a telegraphic receiver mounted thereon including a bracket for supporting the vibrating arm, a strip secured at its intermediate portion 130

to said bracket, a pair of blocks of insulation interposed between said strip and said bracket, said strip having its terminals extended in opposite directions, a telephonic transmitter mounted on one terminal of said strip in electrical communication therewith, a conducting strip having one terminal secured to one of the terminals of the telephonic transmitter and its other end interposed between the blocks of insulation, a spring finger having one terminal secured between said blocks of insulation and in electrical communication with the conductors, a switch arm pivotally mounted on the other terminal of the strip, a second spring finger secured at one end to said strip and engaging at its upper end the switch arm to normally urge the same to raised position, a telephonic receiver mounted on said switch arm, a pair of spaced contacts, one at each side of the

first mentioned spring finger, a projection on the switch arm to engage said first mentioned finger to retain the same in engagement with one of the contacts, a third contact finger mounted on the base plate and in insulated relation thereto, and a second projection on the switch arm to momentarily engage the third spring finger during upward movement of the switch arm and electrical connections between the telegraphic receiver, the telephonic transmitter and the telephonic receiver and forming circuits controlled by the movements of said switch arm. 25 30

In testimony whereof I affix my signature in presence of two witnesses.
